UNITED STATES PATENT OFFICE.

FRANK J. HORSTMAN, OF HAVANA, ILLINOIS, ASSIGNOR OF ONE-HALF TO C. F. WOODS,
OF CHICAGO, ILLINOIS.

LANTERN-SLIDE.

1,097,862.

Specification of Letters Patent. Patented May 26, 1914.

Application filed May 7, 1913. Serial No. 765,981.

To all whom it may concern:

Be it known that I, FRANK J. HORSTMAN, a citizen of the United States, residing at Havana, in the county of Mason and State 5 of Illinois, have invented a certain new and useful Improvement in Lantern-Slides, of which the following is a full, clear, concise, and exact description, reference being had to the accompanying drawings, forming a part 10 of this specification.

My invention relates to lantern slides and has for its object the provision of an improved slide of this character which may be introduced into a projector so that an image 15 may be projected upon a screen, which image may represent the time, for instance. This time is given or represented by two hands which are pivotally mounted, which hands are free to swing around a horizontal 20 axis in conjunction with, say a dial, should my invention be applied for time indicating purposes. In this particular form of the invention the hands though free to rotate, when rotated will come to rest to indicate a 25 predetermined hour of the day depending upon how certain adjustments are made upon each hand. These adjustments in the particular embodiment herein shown consist of the movement of adjustable weights, which 30 weights are so arranged upon the hands in connection also with numerals that the hands will come to rest in a position on the large dial corresponding to the position occupied by the weight of the particular hand 35 as indicated upon the small dial provided upon each hand.

I will explain one form which my invention may take in connection with the accompanying drawing illustrating such embodiment in which—

Figure 1 is a front view of a lantern slide constructed in accordance with my invention; Fig. 2 is a sectional view on line *a—a* of Fig. 1; Fig. 3 is a detail view of the setting mechanism, and Fig. 4 is a sectional view on line *b—b* of Fig. 3.

This embodiment of the invention consists of a transparent slide 1 having a suitable frame 2 for stiffening purposes. Upon 45 this transparent slide 1 a suitable shaft 3 is mounted, which shaft is suitably held in place by means of nuts 4, 4. This shaft carries two hands which are preferably placed on opposite sides of the transparent slide 1

in order to maintain the same in better 55 alinement, suitable nuts 5, 5 being provided to hold these hands in place. These hands 7 and 8 respectively are adapted to coöperate with a dial 9 provided upon the transparent slide 1. The dial, of course, is shown 60 upside down in order that it may be projected in its proper way upon the screen. Each hand is provided with a small protruding shaft 10 to which a weight 11 is pivotally secured through the agency of a 65 projecting arm 12. There is of course sufficient frictional engagement between the arm 12 and the shaft 10 so that the weight 11 will occupy any position into which it is placed when set. Each hand has a circular 70 plate 13 upon which suitable numerals 14 are placed which correspond to the numerals of the clock and in connection with which numerals the pointer 15 is supposed to be used. Whenever therefore it is de- 75 sired to have these hands indicate any certain time, say eighteen minutes past one, for instance, as shown in the illustration, then the weights occupy the positions as shown in Fig. 1, the pointers 15 pointing 80 substantially upwardly, at which time the hands will indicate that particular time desired. The numerals 14 are of course so arranged that the pointer 15 may be set for each hand to the particular time desired, 85 whereafter the slide is placed in the machine and the hands 7 and 8 both swing around their shaft 3, thus showing upon the screen two hands swinging around a central axis. After the elapse of a certain time naturally 90 these hands will come to rest and indicate the time for which these hands were set, thus presenting a rather interesting problem to the audience as to how these hands adjust themselves to the proper time, it being assumed of course that the time indicated for instance might be the correct hour 95 of the day or might be some other predetermined hour of the day at which some other performance or part of performance is 100 to take place, at which time the slide would be used possibly with some explanatory lettering.

From what has been described, it is thought the nature of my invention will be 105 apparent as will also the fact that many changes and modifications may be made without departing from its spirit.

Having however thus described one form which my invention may take, what I claim as new and desire to secure by Letters Patent is:

- 5 1. A lantern slide having a framework, means upon said framework for carrying a pair of pivotally mounted hands, adjustable weights provided upon one or the other of said hands so that said hands after being 10 swung come to rest in a predetermined position, and a dial carried by said framework with which said hands coöperate.
- 15 2. A lantern slide having a framework, means upon said framework for carrying a pair of pivotally mounted hands, adjustable weights provided upon said hands so that said hands after being swung come to rest in a predetermined position, and a dial carried by said framework with which said 20 hands coöperate.
- 25 3. A device of the character described having a dial, a plurality of pivotally mounted hands associated with said dial, adjustable weights provided upon said hands so that said hands after being swung come to rest in a predetermined position, and a transparent slide upon which said dial is marked.
- 30 4. A device of the character described having a dial, a plurality of pivotally mounted hands associated with said dial, adjustable weights provided upon said hands so that said hands after being swung come to rest in a predetermined position, said hands being arranged upon opposite sides of said 35 dial, and a transparent slide upon which said dial is marked.
- 40 5. A device of the character described having a dial, a plurality of pivotally mounted hands associated with said dial, adjustable weights provided upon said hands so that said hands after being swung come to rest in a predetermined position, said hands being arranged upon opposite sides of said dial, a transparent slide upon which said

dial is marked, and indicating means provided upon each hand in conjunction with the weights for setting purposes. 45

6. A lantern slide having a framework, means upon said framework for carrying a pair of pivotally mounted hands, manually adjustable weights provided upon said hands so that said hands after being swung come to rest in a predetermined position, and a dial carried by said framework with which said hands coöperate. 50

55 7. A lantern slide having a frame, a transparent membrane carried by said framework, a dial marked upon said membrane, and a pair of hands coöperating with said dial, said hands being provided with adjustable weights so that said hands after being swung come to rest in a predetermined position. 60

8. A lantern slide having a frame, a transparent membrane carried by said framework, a dial marked upon said membrane, and a pair of hands mounted upon opposite sides of said membrane and coöperating with said dial, said hands being provided with adjustable weights so that said hands after being 65 70 swung come to rest in a predetermined position.

9. A lantern slide having a frame, a transparent membrane carried by said framework, a dial marked upon said membrane, and a pair of hands mounted upon opposite sides of said membrane and coöperating with said dial, said hands being provided with manually adjustable weights so that said hands after being swung come to rest 75 80 in a predetermined position.

In witness whereof, I hereunto subscribe my name this 3rd day of May, A. D., 1913.

FRANK J. HORSTMAN.
